UNITED STATES PATENT OFFICE.

ANNETTE HOWE CARPENTER, OF DENVER, COLORADO.

DESIGN FOR A GAME-BOARD.

SPECIFICATION forming part of Design No. 34,640, dated June 11, 1901.

Application filed May 21, 1901. Serial No. 61,312. Term of patent 7 years.

To all whom it may concern:

Be it known that I, ANNETTE HOWE CARPENTER, a citizen of the United States, residing at Denver, in the county of Arapahoe and State of Colorado, have invented and produced a new and original Design for Game-Boards, of which the following is a specification.

The accompanying drawing shows a plan of a game-board with my design applied.

The essential feature of my design is the game-board A, having the cross-shaped figure B, the central portion of which contains the triangular figures C and the arms D, of which each contains the large rectangular figure E, the smaller rectangular figure F, and

the end figures G. Each end figure G is shown as having a curved outer end, and opposite the end of each arm there is a small circular figure H.

This game-board is designed for playing an improved game of hop-scotch.

I claim—

The design for a game-board substantially as herein shown and described.

In testimony whereof I have hereunto subscribed my name.

ANNETTE HOWE CARPENTER.
